(57) **CLAIM**

The ornamental design for a magnet mount, as shown and described.

DESCRIPTION

FIG. 1 is a front, top perspective view showing my new design;

FIG. 2 is a front view thereof, the rear view, right side view, and left side view being a mirror image thereof, respectively;

FIG. 3 is a top plan view thereof;

FIG. 4 is a bottom plan view thereof;

FIG. 5 is a cross-sectional view thereof as taken along the line 5-5 of FIG. 2; and,

FIG. 6 is a reference perspective view thereof showing an example of usage.

The broken lines in the drawings illustrate portions of the magnet mount that form no part of the claimed design.
